UNITED STATES PATENT OFFICE.

ARTHUR PAGE PHILLIPS, OF HAVERHILL, MASSACHUSETTS, ASSIGNOR TO CROSBY STEAM GAGE AND VALVE COMPANY, OF BOSTON, MASSACHUSETTS, A CORPORATION OF MASSACHUSETTS.

RECORDING-COUNTER.

No. 926,763.

Specification of Letters Patent.

Patented July 6, 1909.

Application filed November 9, 1908. Serial No. 461,687.

To all whom it may concern:

Be it known that I, ARTHUR PAGE PHILLIPS, a citizen of the United States, and resident of Haverhill, in the county of Essex and 5 State of Massachusetts, have invented certain new and useful Improvements in Recording-Counters, of which the following is a specification.

My invention relates to recording counters 10 and its object is to provide means for accurately recording the number of revolutions, reciprocations or similar operations in the machine to which the recorder may be attached; and also means for quickly recording 15 the total of such operations and resetting the machine. It is an improvement on the recording counter described in Letters Patent of the United States issued to Frank L. Wolfe October 15, 1907, and numbered 20 868,055.

The improvement consists in mechanism comprising few and simple parts adapted to produce upon a chart a series of circles concentric therewith, whereby most accurate 25 records are obtained.

It is illustrated by the accompanying drawings in which—

Figure 1 is a plan view of the counter. Fig. 2 is a plan view of the counter with the 30 chart and disk and pencil arm removed. Fig. 3 is a section on the line 3—3 Fig. 2. Figs. 4 and 5 are detailed views.

Similar characters refer to similar parts throughout the several drawings.

The mechanism is mounted on the frame 1 secured to the case 2. The reciprocating rod 3 extends through the case and frame and is furnished near its inner end with the shoulder 4 which engages said frame and limits 35 the outward travel of said rod. The reciprocating rod at its inner end engages the arm 5 rotatably mounted on the stud 6 and controlled by the spring 7 secured thereto and to the plate. The driving pawl 8 is secured 40 to said arm 6 and engages the ratchet wheel 9 rotatably mounted on the stud 10 and engaged by the retaining pawls 11 and 11^a.

The hub of the ratchet wheel comprises a pinion 12 which engages the gear 13 rotatably mounted on the stud 14, whereon is 45 also rotatably mounted the spool-shaped sleeve 15 which rests upon said gear 13 and is driven frictionally thereby. The bar 16 is secured to the studs 17, 17^a, in the frame and 50 has a central aperture which engages a

groove in said sleeve 15 and forms a bearing therefor. The annulus 18 encircles the stud 14 and is secured to the outer face of the sleeve 16 by the pin 19 so as to rotate therewith.

The sleeve 15 carries the stud 20 adapted to engage and actuate, once during each complete rotation of the gear 13, the arm 21 rotatably mounted on the frame and having a forked outer end 22 which straddles the stud 23 mounted on the stud 17 and engages the controlling spring 24 disposed on said stud 23. On this arm 21 is rotatably mounted the driving pawl 25 controlled by the spring 26 mounted on said arm and furnished with the stud 27; said driving pawl is normally in engagement with the sector 28 carrying on its outer end a shaft 29 journaled in the frame and controlled by the spring 30 mounted on said shaft. This sector is engaged by the retaining pawl 31 mounted upon the lever 32 fulcrumed at its inner end on the stud 14 and carrying on its outer end a stud 33 adapted to engage the holes 34 and 34^a in the case. On the sector shaft 29 is 70 mounted the pencil arm 35 carrying the pencil 75 36.

The reciprocating rod 3, as shown in the drawings, is actuated by a rotary rod 3^a journaled in the case and carrying on its inner end the cam 3^b which engages said reciprocating rod 3. Provision is made for actuating arm 5 by means of the shaft 37 journaled in the case and in the frame, furnished at its inner end with the arm 38 90 adapted to engage and operate the arm 5, and at its outer end with the handle 39. The chart 40 encircles the stud 14 between the sleeve 15 and the annulus 18, being secured in place by the pin 19. The thumb nut 40^a, being screwed tightly upon the stud 14, holds the sleeve 15 firmly against the gear 13 so that said gear, said sleeve, said annulus and said chart all rotate together, said sleeve being driven frictionally by said gear. The 95 chart is graduated, as shown, or as may be desired, and rotates in the direction indicated by the arrow 41. Upon the chart at any desired intervals are radial arcs 42 marked 10, 20, 30, 40 and 50 to indicate the 100 number of rotations of the chart. The 105

The operation of the machine is as follows: The parts are normally in the position shown in Figs. 1 and 2 (except that the pencil normally points to zero on the chart), and the 110

outer end of the reciprocating rod 3 engages some part of the machine (not shown) whose revolutions, reciprocations or other movements are to be recorded. At each reciprocation of the rod 3 the driving pawl 8 drives the ratchet wheel 9 one tooth and through the intermediate pinion and gear rotates the sleeve 15 and chart carried by said sleeve a distance equal to one one-thousandth of its circumference, so that each rotation of the chart records one thousand reciprocations of the rod. The pencil 36 describes almost a complete circle upon the chart moving beneath it; but when the circle is nearly completed the stud 20 has been carried around into engagement with the arm 21 (Fig. 4) which it forces outwardly until said stud drops into its original position (shown in Fig. 2), releasing said arm and permitting it to return to its normal position driven by its controlling spring 24 and causing the driving pawl 25 mounted on said arm to drive the sector 28 inwardly one tooth, thereby carrying the pencil inwardly a certain distance preparatory to its describing another circle upon the chart as it continues to rotate beneath it. The numbers 10, 20, 30, 40 and 50 upon the radial arc 42 indicate the number of complete rotations of the chart or the number of thousands of reciprocations of the rod. To find the total number of reciprocations, the lever 32 is moved to the left thereby disengaging the driving pawl 25 and retaining pawl 31 from the sector 28, whereupon the sector is returned to its normal position by the controlling spring 30 carrying with it the pencil, and making a record, as shown in Fig. 1, of twenty-six thousand and some ninety odd reciprocations, the exact reading being concealed in the drawing by the pencil. To reset the machine, that is to bring the zero point on the chart under the pencil, the operator moves the lever 32 to the left thereby releasing the sector 28 from the pawls 25 and 31 and permitting the spring controlled sector 28 to return automatically to its position shown in Fig. 2; he then rotates the chart support (sleeve 15) to the left until the stud 20 is in the position shown in Fig. 2; he then moves said lever 32 to the right causing the pawls 25 and 31 to again engage the sector 28.

The pen-arm 35 with its pen 36, which, as shown in the drawings, is fixed to the shaft 29 of the sector 28, may be of any desired description, or any other recording means may be employed; and when I use the terms pen and pen-arm in the claims I mean thereby

to cover any recording means actuated by 60 the sector.

Having described my invention what I claim and desire to secure by Letters Patent is:—

1. A recording counter comprising a case 65 and mounted therein a reciprocating rod; mechanism including a centrally disposed rotary gear actuated by said reciprocating rod; a rotary chart support mounted on said rotary gear and actuated thereby; a spring 70 controlled lever carrying a spring controlled pawl and actuated by said chart support; a spring controlled toothed sector actuated by said pawl; a second lever under the control of the operator and adapted to throw said 75 pawl into and out of engagement with said sector and a pen and pen-arm carried by said sector; substantially as described.

2. A recording counter comprising a case and mounted therein a reciprocating rod; a 80 rotary chart support rotated through intermediate mechanism by said reciprocating rod; a spring controlled tooth sector actuated through intermediate mechanism by 85 said chart support; said intermediate mechanism and a pen and pen-arm carried by said sector; substantially as described.

3. A recording counter comprising a case and mounted therein a reciprocating rod; a rotary chart support rotated through intermediate mechanism by said reciprocating rod; a spring controlled toothed sector actuated through intermediate mechanism by 90 said chart support; said intermediate mechanism; a pen and pen-arm carried by said 95 sector; together with means for resetting the machine; substantially as described.

4. A recording counter comprising a case and mounted therein a reciprocating rod; a rotary chart support rotated by said reciprocating rod; a spring controlled sector actuated by 100 said chart support and a pen and pen-arm carried by said sector; substantially as described.

5. A recording counter comprising a case 105 and mounted therein a reciprocating rod; a rotary chart support rotated by said reciprocating rod; a spring controlled sector actuated by said chart support; a pen and pen-arm carried by said sector; together with 110 means for resetting the machine; substantially as described.

In testimony whereof I have affixed my signature in presence of two witnesses.

ARTHUR PAGE PHILLIPS.
